In Germany July 12, 1938

4 Claims. (Cl. 235—59)

This invention relates to typewriting calculating machines of the type in which totalizer orders are operable seriatim.

The invention deals with a machine in which, upon operation of a total key, a cam is power-driven in cycles of rotation, one cycle for each totalizer order. Spring urged mechanisms first follow the cam to control and effect the total-taking functions, such as unlocking the totalizer, connecting a zeroizing and selector device to the totalizer, and actuating the zeroizing and selector device. After such functions have been effected in dependence upon spring power, the power operated cam restores the mechanisms.

An object of the invention is to reliably carry out the total-taking operations.

To this end, a further object of the invention is to provide auxiliary devices by the operation of which functions, such as mentioned, are effected and the primary spring drive is correspondingly relieved.

A further object of the invention is to provide an auxiliary device operable to counteract overthrow which might occur due to back lash in certain parts of the totalizer drive.

The foregoing and other objects, features, and advantages will hereinafter appear.

In the accompanying drawings:

Fig. 1 is an elevation of the front part of the machine, viewed from the left.

Fig. 2 is a perspective of parts shown in Fig. 1, certain elements being shown separated for clearness.

Fig. 3 is a partly sectional elevation, viewed from the left, of the slide for unlocking the totalizers, and the mechanism under the control of the slide.

Fig. 4 is an elevation of the mechanism viewed from the right of Fig. 3.

Fig. 5 is a detail from Fig. 4.

Fig. 6 is a perspective of a selector shaft and associate rack.

Fig. 7 is a perspective illustration of the main locking and main calculating shafts, with the zero setting slide and other elements connected to the shafts.

Fig. 8 is a detail of Fig. 7.

Fig. 9 is a left side elevation of the machine.

Fig. 10 is a perspective of parts shown in Fig. 9.

1. General description of the machine

Referring now to the drawings, Figs. 1 and 2, a paper carriage 2 is mounted to reciprocate on the machine frame 1. Column totalizers 4 are secured on the totalizer suspension rail 3 of the 55

paper carriage 2. Totalizer-operating mechanism is arranged in part in a casing 5, at the front plate of the machine, which includes the left-hand side plate 59, Fig. 2. Two cross totalizers 8 are on a carrier 7 movable along tracks 6 on the frame work. The cross totalizers 8 may be carried along by that column totalizer 4 which moves into active position, as shown, for example, in the Patent No. 2,046,524.

A typewriting key board 9 is arranged in the machine frame 1, and a calculating and a decimal tabulator key board, are arranged in a bearing frame 10 below the machine frame 1. Further, a total key 11 with a key bar 11a for the column totalizers 4 is arranged in the bearing frame 10 at the left, and two total keys not shown for the two cross totalizers 8 are arranged in the frame at the right.

A square driving shaft 16, Fig. 2, is journaled in the bearing frame 10, the bearing 35 for the driving shaft in the left-hand side plate of the frame being shown. A motor, not shown, with a suitable reduction gearing, is arranged at the right-hand side of the machine and rotates the driving shaft 16 continuously in clockwise direction, as indicated by the arrow 183.

2. Totalizer-unlocking mechanism

A rotary control unit comprises a pair of cam plates 14 and 15 (Fig. 2) which are rigidly connected to each other and are mounted on the rounded edges of the square portion of the driving shaft 16 so that the unit, when arrested, will not interfere with the rotation of the shaft. A dog 12 (Figs. 1 and 2) is mounted to slide on the unit 14, 15, and a spring 11b (Fig. 2) tends to move the dog 12 into engagement with a pinion 13 keyed to the square portion of the driving shaft 16.

Upon depression of the total taking key 11 (Fig. 1) for the column totalizers 4, or of one of the not shown total keys for the two cross totalizers 8, the dog 12 is released and is moved by its spring 11b to engage the pinion 13 so that the unit 14, 15 rotates with the shaft 16.

An unlocking slide 17 (Figs. 3 and 4), is guided vertically in the machine, and a pair of springs 19 which are attached to the slide 17 at their upper end and anchored in a transverse plate of the machine frame 1 at their lower end, hold a roller 18 at the lower end of the slide 17 against the edge of the cam plate 14. When the elevated portion of the cam plate 14 has moved from below the roller 18 upon the clockwise rotation of the unit 14, 15, the slide 17

descends in the direction of the arrow 65 under the action of its springs 19. An incline 20 near the upper end of the unlocking slide 17 now engages a lug 21 at the free end of an arm 23 which engages a lug 24 (Fig. 5) on a companion arm 25 keyed on the main locking shaft 22, turning the shaft 22 and causing the unlocking of the calculating mechanism. A forked arm 26 is keyed on the shaft 22 and engages a pin 27 at the upper end of a lever 28. The lever 28 is fixed on a rotatably mounted shaft 29. A spring 23a is attached to the lower arm of the lever 28 and tends to turn it clockwise together with said shaft 29. A further lever 30 also arranged on the shaft 29 is the unlocking member for that cross totalizer 8 which is visible in Fig. 3, and the unlocking member 30 engages a lever 31 in this totalizer. A similar arrangement, not shown, is provided for the other cross totalizer. A lever 32 projects upwardly from the main locking shaft 22 and the clockwise movement imparted to the parts by the means described, causes the lever 32 to unlock that column totalizer 4 which is in active position at the time.

It will appear that the springs 19, in moving down the unlocking slide 17 and operating, through the mechanisms described, the cross totalizer and column totalizer unlocking levers 30 and 32, must overcome the friction of the mechanism which, in addition to the gradual decrease in their tension, tends to interfere with the proper functioning of the machine.

To overcome this drawback, an auxiliary device by which the springs 19 are relieved, is provided according to the invention, as will now be described.

3. The auxiliary unlocking device

The cam plates 14 and 15 are fixed to a sleeve 34 rotatable in the bearing 35 in the left-hand side plate of the lower frame 10 (Fig. 2). The sleeve 34 has a pair of notches 33 in its left-hand end in which engage teeth 37 on a sleeve 36 which is also rotatable in the bearing 35 where a detachable connection is formed between the two sleeves by their notches and teeth. Three cam plates, a right-hand cam plate 38, a left-hand cam plate 39, and a central cam plate 197 (Fig. 10) are secured on the sleeve 36 in any suitable manner. The three cam plates and their sleeve 36 make up the auxiliary controlling unit. The right hand cam plate 38 controls the auxiliary unlocking device, as will be described below. The left hand cam plate 39 controls an auxiliary device for the coupling of the zero setting slide with the main calculating shaft, as will also be described. The central cam plate 197 controls an auxiliary device for operating the selector shaft and the main calculating shaft, as will also be described. By means of rivets 40 in holes 43 of the end cam plate 38, a cam 42 is secured to the outer side of the end cam plate 38, the rivets extending through holes 41 in the cam 42 (Fig. 2).

The sleeve 36 of the auxiliary controlling unit is held engaged with the sleeve 34 of the unit 14, 15 on the driving shaft 16 by an angle bracket 45 which is fixed on the left-hand side plate of the bearing frame 10 by screws 44. The free end 46 (Fig. 2) of the bracket bears against the left-hand face of the end cam plate 39 and holds the teeth 37 on the sleeve 36 in the recesses 33 so that the units may rotate in unison. When the bracket 45 is removed the

auxiliary controlling unit can be detached from the unit 14, 15.

A bellcrank 47 (Figs. 1 and 2) is fulcrumed about a screw 48 in the frame 1. The downwardly directed arm of the bellcrank 47 has a roller 49 which is held against the edge of the cam plate 38 by a spring 41a connected to a pin 47b (Fig. 2) on the horizontal arm of the bellcrank 47 and to a pin 41c of a double-armed lever 121 which is fulcrumed on a bracket secured to the outer side of the machine frame 1. Lever 121 releases the total key which is locked in depressed position during the total taking operation, but is not a part of this invention.

A rivet 51 at the rear end of the horizontal arm of the bellcrank 47 projects at the right-hand side of the arm into a slot 52 in the lower end of a connecting rod 53. A spring 50 attached to a pin 55 on the rod 53 and to the rivet 51 provides a yielding connection between the bellcrank 47 and the connecting rod 53.

A bracket 53a which is secured to the inner side of the rod by two screws 54 is pivotally connected by screw 56 to a bellcrank lever 57 swingable about the reduced end 58 of the main locking shaft 22 at the outer side of the wall 59. This end has a threaded portion 61 for a lever retaining nut 60. The vertical arm of the lever 57 presents a flat face 62 and a tooth 66 at one side of the face. Under the pull of the spring 50, the connecting rod 53 is pulled down in the direction of the arrow 65 until the upper end of its slot 52 bears on the rivet 51 and this holds the lever 57 ready for engaging, with its tooth 66, the rear side of a lug 63 on lever 64 which is keyed on the main locking shaft 22. This shaft, it will be remembered, is provided with the unlocking lever 32 for the column totalizers 4.

At the upper end 81 (Fig. 2) of the connecting rod 53, an angle 82, with a tooth 85, is held by screws 83 projecting in elongated holes 84 in the angle, for a purpose which will be described below.

4. The operation of the auxiliary unlocking device

Upon depressing the total key 11 for the column totalizers 4, or one of the not shown total keys for the cross totalizers 8, the unit 14, 15 and the auxiliary controlling unit rotate clockwise with the driving shaft 16. The unlocking slide 17 is pulled down by its spring 19 and its incline 20 turns the main locking shaft 22 clockwise, as described. The auxiliary unlocking device assists the springs 19 as follows: The rise of the cam plate 38, through the roller 49, turns the bellcrank 47 anti-clockwise about its fulcrum screw 48, whereby spring 50 by which the connecting rod 53 is connected to the bellcrank 47 pulls down the rod 53 (Figs. 1 and 2) in the direction of the arrow 65 to swing the lever 57 which is pivotally connected to rod bracket 53a by the screw 56, clockwise. Tooth 66 of lever 57 acts on the lug 63 of the lever 64, which is keyed on the main locking shaft 22, whereby lever 64, the shaft 22, and the unlocking lever 32 are turned clockwise, and the lever 32 unlocks that column totalizer 4 which is in active position. The turning of the shaft 22 in clockwise direction effects also the unlocking of the cross totalizers 8, through the means illustrated in Fig. 3, that is, the forked arm 26, the pin 27, the lever 28, the shaft 29, and the unlocking arms 30.

It will be understood now that the auxiliary device which is operated by the cam plate 38

of the auxiliary controlling unit, relieves the springs 18.

The yielding connection 50 between the connecting rod 53 and the bellcrank 47 prevents the over-stressing of members if obstruction occurs in the mechanism.

5. Mechanism for coupling the zero setting slide to the main calculating shaft

As described in section 2, the arm 23 (Figs. 3, 4, and 5) is turned clockwise. A pin 68 (Figs. 3 and 5) on the arm 23 engages the upper edge of an arm 69 which is keyed on a coupling shaft 70 arranged below, and at right angles to, the shaft 22, and turns the coupling shaft 70 clockwise against a spring 127 (Fig. 5). The coupling shaft 70 is mounted to turn in bearings, not shown, in the front and the rear wall of the casing 5. The two arms 71 and 72 (Figs. 3 and 4) of a coupling fork are keyed on the coupling shaft 70 and coupling pins 73 and 74 which are riveted into the respective arms at their free ends, engage in an annular groove in the hub 75a of a spur gear 75 (Fig. 4). The spur gear 75 is mounted to slide, but is held against rotation, on the main calculating shaft 76, in that a pair of fingers 77 (Fig. 4) projecting from gear 75 slidably fit slots 78a in the perimeter of a disk 78 which is keyed on the shaft 76. When the coupling shaft 70 is turned clockwise by the pin 68 on the arm 23 and by the arm 69, as described, the arms 71 and 72 (Fig. 7) of the coupling fork move in the same direction and the spur gear 75 is shifted to the right and into mesh with a rack 79 (Fig. 7) at the upper end of a zero setting slide 80. The zero setting slide 80 is mounted for vertical reciprocation in the left hand portion of the totalizer actuating mechanism. In addition to its upper rack 79, the zero setting slide 80 has a bracket with a lower rack 134 which meshes with a pinion 133 on a shaft in the bracket 153 (Figs. 2 and 7).

The auxiliary device by which movement the spur gear 75 into mesh with the upper rack 79 of the zero setting slide 80 is reliably effected, will now be described.

6. The auxiliary coupling device

As mentioned in section 3, an angle 82 (Figs. 1 and 2) with a tooth 85, is adjustably secured to the connecting rod 53. The lower edge 93 (Figs. 1 and 2) of the forwardly extending tooth 85 is above the upper edge 86 (Fig. 2) of an auxiliary coupling bellcrank 87, which, as shown in Fig. 2, is fulcrumed about a screw 88 in a bracket 89 secured to the outer side of the wall 59. The tail end 91 of the bellcrank projects through a slot in the wall 59 and is held against the arm 72 of the coupling fork on the shaft 70 by the weight of the heavier outer arm 87.

7. The operation of the auxiliary coupling device

Upon descent of the connecting rod 53 in the direction of the arrow 65, as described in section 4, the lower edge 93 of the tooth 85 which projects from the angle 82 on the upper end of the connecting rod 53, engages the upper edge 86 (Fig. 2) of the bellcrank 87 and turns the bellcrank 87 anti-clockwise about the screw 88 whereby the tail end 91 of the bellcrank 87 bearing on the arm 72 turns the coupling fork 71, 72 and the coupling shaft 70, clockwise to move the spur gear 75 (Figs. 3, 4 and 7) to the right on the main calculating shaft 76, and into mesh with

the upper rack 79 (Fig. 7) of the zero setting slide 80.

By the auxiliary device described, a rapid and reliable coupling of the spur gear 75 with the zero setting slide 80 is effected on the one hand, and on the other hand the springs 18 (Figs. 3 and 4) of the unlocking slide 17 are assisted in their function of coupling the spur gear 75 with the rack 79 of the unlocking slide 80.

An auxiliary device is also provided for the mechanism by which the spur gear 75 is uncoupled from the rack 79 of the zero setting slide 80, as will now be described. Reference will first be had to

8. The mechanism for uncoupling the zero setting slide from the main calculating shaft

A downwardly extending arm 94 (Figs. 2 and 7) is keyed on the coupling shaft 70. As the shaft is turned clockwise, the tooth-shaped lower edge 95 of the arm 94 overrides a tooth 96 (Fig. 7) at the right-hand end of a latch 98, pivoted on a bolt 97, so that tooth 96 engages behind the arm 94 under the action of a spring 98a attached to the left-hand end of the latch 98 and holds the shaft 70 in its coupling position.

After the typewriting operation which is started by the zero setting slide through known means which will not be described, because the means form no part of the invention, has been completed, a slide 99 which is arranged for vertical displacement at the left of the casing 5 of the calculating mechanism is raised by the typewriting means against the arrow 65, and swings the latch 98 whose left-hand end extends into a hole 100 in the slide 99, clockwise about the bolt 97. A rocker 99a engages with the left-hand arm in a hole 99c (Fig. 7) in the slide 99 which is above the hole 100 and its right hand arm bears against the arm 94 on the coupling shaft 70. As the slide 99 is raised, the rocker 99a is swung clockwise about its fulcrum 99b in a suitable bracket and acts on the arm 94 to turn said arm and the coupling shaft 70, with the arms 71, 72 anti-clockwise, thereby shifting the spur gear 75 to the left and out of mesh with the upper rack 79 of the zero setting slide 80.

In order to effect a more reliable uncoupling of the spur gear 75 from the zero setting slide 80, the auxiliary uncoupling device is provided, and may be used instead of the uncoupling device just described.

9. The auxiliary uncoupling device

Referring now to Figs. 1 and 2, a slide 103, with slots 102 (Fig. 2) in its upper and lower crooked ends, is guided by a screw 101 engaging in the upper slot and secured in the side wall 59 of the casing 5 for the calculating mechanism, and by a screw 101 engaging in the lower slot and secured in the left-hand side plate of the machine frame 1, so that the slide can reciprocate vertically. A lug 104 at the lower end of the slide 103 supports a roller 105 (Fig. 2) for cooperation with the cam 42 on the cam plate 38 in the controlling unit. The releasing lever 121 to which the upper end of the spring 47a is secured at 47c, as described, is pivotally connected to the slide 103 at 122 so that the pull of the spring 47a holds the roller 105 in the path of the cam 42, the normal position of the slide 103 being that in which it has been lowered in the direction of the arrow 65 until the upper ends of its slots 102 bear against the screws 101.

A catch 111 (Figs. 1 and 2) is fulcrumed about

a screw 112 in a slot 113 in the left-hand side plate 59 of the casing 5 so that the arm 110 (Fig. 2) of the catch 111 projects from the casing at the left while the arms 114 and 115 of the catch are inside the casing. An abutment 107, with an upper edge 119, is secured to the slide 103 by screws 106. The rear edge of the slide 103 is notched at 109, and the edge 108 of this notch, on the one hand, and an upwardly projecting lug 107a of the abutment 107, on the other hand, 10 guide the outer arm 110 of the three-armed catch 111. The lower inner arm 114 of the three-armed catch 111 has a hook 126 at its free end for engaging the lower edge 95 of the arm 94 on the coupling shaft 70, and its upper inner arm 115 is arranged as a pusher for the left-hand edge 116 (Fig. 2) of the arm 94. A spring 117 which is attached to a pin 110a, Fig. 2, on the outer arm 110 of the catch 111 and to a pin 118 in the left-hand side wall 59 of the casing 5 urges the catch 111 anti-clockwise about its screw 112 and holds the outer arm 110 against the edge 119 of the abutment 107, this being the normal position of the catch 111.

10. The operation of the auxiliary uncoupling device

When the total key 4 for the column totalizers 4 or one of the not shown total keys for the cross totalizers 8 has been depressed the means described in section 7 operate to turn the coupling shaft 70 clockwise to move gear 75 into mesh with the zero-setting slide 80. The arm 94 on the shaft 70 moves in the same direction, its lower edge 95 acts on the tooth 126 (Fig. 2) at the lower inner arm 114 of the catch 111 and turns the catch 111 clockwise about its fulcrum screw 112 against the spring 117 until the tooth 126 engages behind the arm 94 under the reaction of the spring 117 to keep the spur gear 75 in mesh with the rack 79 of the zero setting slide 80.

As described, the auxiliary controlling unit is rotated clockwise with the driving shaft 16 upon operation of a total key. The cam 42 at the cam plate 38 of the controlling unit is so arranged on the cam plate that it acts on the roller 105 at the lower end of the slide 103 and raises the slide against the spring 47a and in the opposite direction of the arrow 65. The edge 119 of the abutment 107 on the slide 103 acts on the outer arm 110 of the catch 111 and turns the catch 111 clockwise about its screw 112 against the spring 117. The tooth 126 at the lower inner arm 114 of the catch 111 releases the arm 94. The coupling shaft 70, its arm 94 and the fork 71, 72 are now turned anti-clockwise by the spring 127 (Fig. 5) which engages the arm 69 on the coupling shaft 70. While this occurs, the upper or pusher arm 115 of the catch 111 bears against the left-hand edge 116 (Fig. 2) of the arm 94 and accelerates the anti-clockwise movement of the arm 94 and the fork 71, 72. By these means, the uncoupling of the spur gear 75 from the rack 79 of the zero setting slide 80 is effected more rapidly and reliable operation of the parts involved is ensured.

11. Description of the device for correcting overthrowing

For a better understanding of this device, it is necessary to explain an undesirable condition which might remain if the said device were not provided.

A transmission member, Fig. 6, comprises a front part 129 and a rear part 128, each with a

rack at its outer end. The inner ends of the parts 128, 129 are fastened together by screw-and-slot connections, Fig. 10, so that the parts may be relatively adjusted lengthwise. The rack at the free end of the front part 129 meshes with a pinion 132 (Figs. 7 and 2) on a shaft 154 (Fig. 7) which is mounted to rotate in the bracket 153. The rack at the free end of the rear part 128 meshes with a pinion 128a (Fig. 6) made in the left-hand end of the selector shaft 171. The ends of the selector shaft 171 are mounted to rotate in the two brackets 128b and 128c illustrated in Fig. 6. The arrangement of the transmission member 128, 129 with respect to the pinion shaft 154 (Fig. 2) and the selector shaft 171 (Fig. 6) is shown in Fig. 9, it being understood, however, that the means for moving the transmission member to the front in the direction of the arrow 131 is a spring 130 in the example illustrated in Fig. 6, and a system of levers in Figs. 9 and 10, as will be described later.

During the total taking operation the spring 130 moves the transmission member 128, 129 to the front in the direction of the arrow 131 and this causes the zero setting wheel 142 (Fig. 7) to be rotated in conformity with the value present in the corresponding calculating place of that cross totalizer 3 from which the total is taken, until the active numeral wheel indicates "0", by the following mechanism illustrated in Figs. 7 and 8. The pinion 132 on the shaft 154 meshes with the rack of the front part 129 and the pinion 133 at the right-hand end of the shaft 154 meshes with the lower rack 134 on the zero setting slide 80. The upper rack 79 of the slide 80 meshes with the spur gear 75 and rotates the main calculating shaft 76. The main calculating shaft 76 may operate shaft 138 in a given direction through gearing 135, 136, 137 and in the opposite direction through gearing 135 and 139. The rotation of the shaft 138 drives a gear 140 and an intermediate gear 141. The active numeral wheel indicates "0", when one of the zero setting teeth 143 on the wheel 142 engages the zero setting stop 144.

Due to the inevitable slack or back lash in the train of mechanisms 132 to 142, the spring 130 of the transmission member 128, 129 tends to overthrow the main calculating shaft 76 and a train of gears 145, 146, 147, 148 (Fig. 7) which connect the shaft 76 to an intermediate shaft 193. When this occurs, the driving wheel 149 (Figs. 7 and 8) on the intermediate shaft 193 by which the driving wheel 152—Fig. 3—of that column totalizer 4 which is in active position, is to be rotated, is thrown too far in the direction of the arrow 150 in Fig. 8 so that the pawl 151 on the main locking shaft 22, instead of engaging between the teeth of the driving wheel 149, rides on the tooth following this gap, as shown in Fig. 8. When the value has been withdrawn from the cross totalizer 8, and been typed on the paper supported by the carriage 2, and the carriage now moves a step, a tooth of the driving wheel 152 of that column totalizer 4 which is in active position, collides with one of the teeth of the driving wheel 149, instead of entering properly into the corresponding gap. This leads to disturbances in the function of the machine.

Trouble of this sort is eliminated for the train of mechanism 145—142 by a pawl 151a (Fig. 7) on the main locking shaft 22 engaging a locking wheel 151b on the main calculating shaft 76.

For the train of mechanism including the driv-

ing wheel 149 on the intermediate shaft 193, trouble is eliminated as follows:

The left-hand end of the shaft 154 (Figs. 1 and 2), or the left-hand end of the shaft-pivoting screw, Fig. 4, in the bracket 153 extends into a slot 155 in the upper end of an aligning slide 156, as shown in Fig. 2, and guides the upper end of this slide. A nut 158 is placed on a threaded portion 157 at the end of the shaft or screw so that the slide 156 is held on the shaft 154. At its lower end, the aligning slide 156 is guided by a headed screw 159 extending through a slot 160 and secured in the bracket 48. A roller 161 is arranged at the inner side of the aligning slide 156 for cooperation with the left-hand cam plate 39 of the controlling unit, and a spring 162 whose upper end is connected to the aligning slide 156 and whose lower end is anchored on the fulcrum screw 48 of the bellcrank 47 which cooperates with the cam plate 38 at the right of the controlling unit, as described, pulls the aligning slide 156 downwards in the direction of the arrow 65, holding the roller 161 on the slide 156 against the cam plate 39.

A support 163 is adjustably secured to the outer side of the aligning slide 156 by screws 164. A lug 163a (Fig. 2) projects to the right and the front from this support 163 and a screw 165 is inserted in a hole in the lug. A pawl 166 is pivoted on the screw 165 for cooperation with a ratchet wheel 167 on the shaft 154. A spring 168 (Fig. 2) whose rear end is attached to a pin 169 on the aligning slide 156 and whose front end engages a pin 170 on the pawl 166, turns the pawl 166 anti-clockwise about the screw 165, and throws it into a gap of the ratchet wheel 167.

12. The operation of the correcting device

When one of the not shown total keys for the cross totalizers 8 is depressed, the unit 14, 15, together with the auxiliary unit 38, 39, 197, are rotated with the continuously rotating driving shaft 16, as described, and, when the cam plate 39 of the unit has rotated about 45 degrees, the roller 161 on the aligning slide 156 descends from the elevated portion of the cam plate 39 to its depressed portion under the action of its spring 162. The aligning slide 156 descends in the direction of the arrow 65, and the pawl 166 which is pivoted on the support 163 of the slide, descends with it and is moved out of engagement from the ratchet 167 on the shaft 154, whereupon the spring 168 turns the pawl anti-clockwise about the screw 165 until its pin 170 is arrested by the upper edge of the support 163. Zero setting now occurs as described in section 11, and the driving wheel 149 (Fig. 7) on the intermediate shaft 193 is moved into the position shown in Fig. 8, with respect to the pawl 151 on the main locking shaft 22. When the cam plate 39 of the controlling unit has performed about half a revolution, the elevated portion of the cam plate 39 again engages the roller 161 on the aligning slide 156, raising the slide against its spring 162, and in opposite direction to the arrow 65. The pawl 166 which, as described, is pivoted on the support 163 of the slide 156, rises with the slide and imparts to the ratchet wheel 167 a small partial rotation in counterclockwise direction. This partial rotation is transmitted to the driving wheel 149 on the intermediate shaft 193 through the pinion 133 on the shaft 154, the lower rack 134 on the zero setting slide 80, its upper rack 79, the spur gear 75, the main calculating shaft 76, and the train 145 to 148. The driving wheel 149 is thereby

turned against the direction of the arrow 150 (Fig. 8) until the tooth of the pawl 151 is able to engage properly in the corresponding gap between the teeth of the driving wheel 149. The driving wheel 149 thereby has its teeth aligned for meshing with the driving wheel 152 of that column totalizer 4 which is in active position.

By these aligning means, the selector shaft 171 is also adjusted properly.

10 13. The transmission mechanism between the main calculating shaft and the selector shaft

When the unlocking slide 17 (Figs. 3, 4, 9 and 10) descends, as described in sections 2, 3, and 4, an L-shaped dog 184 on the slide 17, as shown in Figs. 3, 4 and 10, engages the free end of a bellcrank 185 (Fig. 4) which is mounted to swing about a rivet 190 in a suitable bracket at the left of the zero setting slide 80. A pawl 188 is fulcrumed on the same rivet 190 with the bellcrank 185 for locking the zero setting slide 80 against downward movement, and a lug 187 is provided on the pawl 188 against which the lower edge of the horizontal arm of the bell crank 185 is held by a spring 186 engaging the tail end of the bellcrank 185. A spring 189 holds the pawl 188 in engagement with a rack 191, Fig. 10, fastened to the zero setting slide 80 by a pair of pins.

30 When the unlocking slide 17 descends in the manner described, its dog 184 engages the free end of the bellcrank 185 and turns the bellcrank clockwise. Through the lug 187, the pawl 188 is also turned clockwise and out of engagement with the rack 191, so that the zero setting slide 80 is now unlocked and free to descend. The spring 130 now becomes active and pulls the transmission member 128, 129 toward the front in the direction of the arrow 131, and, through pinions 132 and 133 on the shaft 154, and the lower rack 134 on the zero setting slide 80, moves the slide downwards. Through its upper rack 79, the spur gear 75, the main calculating shaft 76, the train of gears 145 to 148, the intermediate shaft 193, and the driving wheel 149, the zero setting slide 80 rotates that driving wheel 152 of the column totalizer 4 which is in active position and from which the total is taken.

40 In addition to the other gearing of the corresponding calculating place, the active zero setting wheel 194a, as shown in Fig. 10, is also rotated until it is arrested by one of its zero setting teeth 195 abutting against the zero stop 196 which has been raised into active position.

45 This zero setting operation as effected by the spring 130 has the following drawback: When, for instance, lower values, such as "1," "2," or "3" were withdrawn from a calculating place of a totalizer, the spring 130 was not contracted to any considerable extent and so the full accumulated energy of the spring 130 which was abruptly released by removing the pawl 188 from the rack 191 on the zero setting slide 80, caused a severe blow of one of the zero setting teeth 195 against the zero stop 196. On the other hand, for the withdrawing of higher values, such as "8" or "9," or "10" or "11" in machines for British currency, the distance traveled by the transmission member is so long, as the spring 130 is contracted to such an extent that its energy is insufficient for overcoming the resistance of the mechanism, and this often causes miscalculation.

70 75 This is avoided according to the invention by

the equalizing device which will now be described.

14. The tension equalizing device

Referring now to Figs. 9 and 10, a double-armed lever 199 is mounted to swing about a screw 203 in a support 202 (Fig. 10) screwed into the machine frame 1 at its left-hand side. A roller 198 is mounted to rotate about the rivet 200 in lever 199 for cooperation with the central cam plate 197 of the auxiliary controlling unit. The lower end of a T lever 201 is also fulcrumed on the screw 203, adjacent lever 199. A spring 205 connects a rivet 204 at the upper end of the double-armed lever 199 to a rivet 206 at the rear end of the T lever 201 and holds an eccentric abutment 207 on the T lever 201 against the double-armed lever 199. The relative positions of levers 199, 201 can be varied by turning abutment 207 about a screw 208 and clamping it by a nut 209. The upper end of the T lever 201 has a slot 210 which engages a pin 211 in the front part 129 of the transmission member 128, 129. In the normal position of the transmission member (Figs. 9 and 10) the roller 198 at the lower end of the double-armed lever 199 is on the edge of the central cam plate 197.

By way of comparison, the spring 130 of Fig. 6 has been shown in dot-and-dash lines in Fig. 9 but it is understood that the spring 130 is not provided in Figs. 9 and 10 but is replaced by the spring 205.

15. The operation of the equalizing device

If it is desired to withdraw from a column totalizer 4 which is in active position, the value which has been calculated therein, the total key 11 is depressed, whereupon the unit 14, 15 and the auxiliary unit 38, 39, 197 are rotated in the direction of the arrow 183, as described.

After a short time, the short rise 212 (Fig. 10) of the central cam plate 197 acts on the roller 198 of the double-armed lever 199 and swings this clockwise for some distance. Tension is thereby put on the spring 205 in that the lever 201 and its eccentric 207 are held by means of the locked zero setting slide 80.

The unlocking slide 17 descends on the descending portion of the cam plate 14 as the unit 14, 15 rotates in the direction of the arrow 183. A lug 180 (Fig. 10) on the descending unlocking slide 17 drops from and releases an arm 181 on which bears an eccentric 182 of slide 80. In consequence, the zero setting slide 80 and the pinions 132 and 133 on the shaft 154 are released. The somewhat tensioned spring 205 pulls the transmission member 128, 129 in the direction of the arrow 181 by turning the T lever 201 clockwise about the screw 203 until its eccentric 207 again bears against the rear edge of the double-armed lever 199. By the connection 210, 211 the transmission member 128, 129 is pulled in the direction of the arrow 181 by the spring 205 and the zero setting slide 80 is lowered by the pinions 132 and 133, and its lower rack 134, until the lowermost tooth of its angular rack 191 is arrested by the pawl 183. By these means, the zero setting slide 80 is so positioned that the spur gear 75 on the main calculating shaft 76 when it is shifted to the right by the fork 11, 12 on the coupling shaft 70, can engage in the teeth of the upper rack 79 on the zero setting slide without obstruction. The lug 184 on the descending unlocking slide 17 now swings the pawl 185 clockwise, as de-

scribed, and disengages it from the teeth of the rack 191.

The elevated portion 213 (Fig. 10) of the rotating control cam plate 197 now acts on the roller 198 of the double-armed lever 199, turning this, and through the spring 205, the T lever 201 clockwise about the screw 203 to move the transmission member 128, 129 further in the direction of the arrow 181 and thereby move the zero setting slide 80 downwards through the pinions 132 and 133 and the lower rack 134. The zero-slide-including train from the T lever 201 to the zero-setting wheel 194a thus is moved or driven by cam 197 until arrested by the stopping of said wheel 194a against the zero stop 196, Fig. 10. The extent of this movement of the train varies, of course, in accordance with the extent of zeroizing rotation of wheel 194a. Following arrest of the train, the clockwise drive of lever 199 by cam 197 may continue independently to its limit in that the spring 205 may correspondingly stretch and will, moreover, impart its force to the train to hold the parts in their positions of arrest. Following the period for maximum zeroizing stroke of the train, the total digit, which has been taken in a calculating place, is typed on the paper which is placed on the paper carriage platen 192 (Fig. 9). When the total has been typed the spur gear 75 is shifted to the left and out of mesh from the rack 79 of the zero setting slide 80. Upon further rotation of the auxiliary controlling unit, the elevated portion 213 (Fig. 10) of the central cam plate 197 releases the roller 198 of the double-armed lever 199 and the spring 205 turns said lever anti-clockwise about its screw 203. At the same time the elevated portion of the cam plate 14 in the unit 14, 15 engages the roller 18 at the lower end of the unlocking slide 17 and raises the slide against the springs 19. The lug 180 of the unlocking slide 17 turns the arm 181 anti-clockwise and, through the eccentric 182, the arm 181 raises the zero setting slide 80. By the ascending movement of the zero setting slide 80, the rack 134 and the pinions 133 and 132 on the shaft 154 return the transmission member 128, 129 into its initial position in the opposite direction of the arrow 181 and the T lever 201 and the double-armed lever 199 anti-clockwise into their initial positions.

These operations occur in every decimal place of the totalizers. When the totalizer which is in active position, has been completely cleared and the total written, the corresponding total key is unlocked, causing the clutch 12, 13 to be opened to uncouple the unit 14, 15 and the auxiliary controlling unit 38, 39, 197 from the driving shaft 16, all parts returning into their initial positions.

By means of the equalizing device, the velocity at which the transmission member 128, 129 and the mechanism connected thereto, are moved, is uniform from beginning to end, when withdrawing from a decimal place of a totalizer a lower value such as "1," "2" or "3" as well as when withdrawing a higher value such as "8" or "9" in the decimal system, or "10" or "11" in machines for British currency. In this manner, the force at which the zero setting teeth 195 strike the zero stop 196, is equalized, noise is reduced, and a more steady operation of the machine is effected. On the other hand, the values in the totalizers, especially higher ones, are withdrawn without fail because the central cam plate 197 invariably drives the zero setting

mechanism until the zero setting has been completed.

The mechanism including the spring 285 and the levers 199 and 201 also prevents overstressing of parts in case of obstruction.

Having now particularly described and ascertained the nature of my said invention, and in what manner the same is to be performed, I declare that what I claim is:

1. In a machine of the character described having a totalizer wheel and a total key, the combination of a power drive, a cam cyclically operable by said drive upon operation of said key, a device transiently operatively connectable to said wheel and differentially operable for zeroizing said wheel, an auxiliary cam operable jointly with the first-named cam by said drive, motion-transmitting means, including a yieldable connection, driven by the auxiliary cam for differentially operating said device to zeroize said wheel, and motion-transmitting means driven by the first-named cam for restoring said device and coincidentally restoring the first-named motion-transmitting means.

2. In a machine of the character described, having a totalizer wheel and a zero stop, the combination with a gear drive operable to turn said wheel to the zero-stop, of a device reciprocable in zeroizing and return movements, means operable to connect said gear drive in train with said device for the time of the zeroizing movement, means operable upon said device for reciprocating said device, said last-named means including a spring to impart the zeroizing movement to the train, the zeroizing movement of at least a part of the train as imparted by the spring being excessive because of back lash in the train, a ratchet associated with said device, a pawl, and means acting to operate the pawl to move the ratchet, at a time between the zeroizing and full-return movements of the device, to return said device part-way to correct the excess movement.

3. In a machine of the character described,

having a totalizer wheel operable to a zero stop, and a total key; the combination with a releasable zeroizing actuator reciprocable in zeroizing and return movements, and a gear train operatively connecting the actuator and wheel during zeroizing of a power shaft, three cams connectable collectively to said shaft upon operation of said key, means following one of the cams to release said actuator, motion-transmitting means, including a spring, cooperative with another one of the cams for operating the actuator in the zeroizing movement, the first-named cam acting subsequently, through the said following means, to operate the actuator in return movement, and means cooperatively with the third cam to return the actuator partly to take up excess movement thereof, said excess movement occurring, under the influence of said spring, because of back lash in the connected actuator and gear train.

4. In a machine of the character described having a totalizer wheel, the combination with a gear-train having a portion intermediate its ends operatively connectible with said wheel, and stop-means operatively connectible with one end of the train to limit differentially the extent of its actuation, of a device reciprocable in gear-train-actuating and return movements, means operable to connect the other end of said gear-train in train with said device for the time of the actuating movement, means operable upon said device for reciprocating said device, said last-named means including a spring to impart the actuating movement to said device, the actuating movement of said portion of the train as imparted by means of the spring being excessive because of back-lash between said portion and the stopped end of the gear train, a ratchet associated with said device, a pawl, and means acting to operate the pawl to move the ratchet, at a time between the actuating and full-return movements of the device to return said device part way to correct the excess movement.

ROBERT ANSCHÜTZ.
